UNITED STATES PATENT OFFICE

CARL GILMORE, OF OAKLAND, CALIFORNIA

SHEATHING PAPER

Application filed June 1, 1929. Serial No. 367,806.

My invention relates to improvements in sheathing paper, particularly useful as weather-proofing and water-proofing means, adapted to be disposed across the woodwork 5 of stucco structures, prior to the application thereagainst of the lath and stucco composition.

One of the objects of the present invention is the provision of sheathing paper having 10 binding strips at spaced intervals secured transversely thereacross, said strips adapted for reinforcing the sheathing paper and for assisting it in resisting wrinkling or crushing or otherwise breaking down, particularly 15 transversely, when handling it or in applying it to the woodwork of a structure, the strips also functioning as reinforcements through which fastening nails, or the like, may be driven for temporarily securing the 20 sheathing paper to the woodwork, prior to the application thereto of the metal lath and stucco composition; a further object is the provision of binding strips relatively softer and more pliable than the body of the sheath- 25 ing paper, whereby said paper, considering said strips as forming part thereof, will have spaced areas of which the inner side portions are relatively harder and less pliable than the outer portions of the same areas, whereby 30 when a nail or other fastening device is projected therethrough from the outer side, as when fastening the paper temporarily to the woodwork of a structure, or in securing the lath thereto, the outer side portion will, first- 35 ly, resist any tearing of said inner side portion by the driving of the nails therethrough, secondly, the outer side portion, comprising soft and pliable material, will remain in close bodily association with the sides of the nail 40 or other fastening device, thereby resisting any possible leakage of water through said outer side portion along the sides of said nails or fastening devices; a still further object is the provision of binding strips formed 45 of paper composition, permanently secured in spaced order across the face of the sheath- ing paper, said strips being thicker and softer than the latter and being adapted to function as a cushion against which furring elements 50 are forced by the driving of the fas-

tening devices used in securing the metal lath to the structure.

With the foregoing and still further objects and purposes in view which will appear as the description proceeds, my invention 55 resides in the arrangement, formation and association of parts and in the details of construction hereinafter described and claimed, it being understood that changes in the precise embodiment of the invention herein disclosed can be made within the scope of what is claimed without departing from the spirit 60 of the invention.

In the accompanying drawings—

Figure 1 is a view in elevation of a small 65 portion of the wall boards of a stucco structure, with a portion of my improved sheathing paper, and a section of wire lath, secured across the face thereof;

Figure 2 is an enlarged edge view of the 70 sheathing paper approximately on line 2'-2' of Fig. 1;

Figure 3 is a still further enlarged sectional view of a fragmental portion of a wall board 75 and sheathing paper, approximately on line 3'-3' of Fig. 1;

Figure 4 is a view similar to that shown in the last preceding Fig. but showing in addition a fastening nail, a strip of metal lath, and a sectional view of a furring element disposed intermediate the sheathing paper and the metal lath;

Figure 5 is a sectional view approximately on line 5'-5' of Fig. 1;

Figure 6 is a view in elevation of small 85 portions of sheathing paper, metal lath, and furring element, secured together by means of a fastening nail; and

Figure 7 is a vertical sectional view of a portion of wall board and sheathing paper, 90 with a strip of wire lath secured thereto by means of a fastening nail.

Referring to the drawings in detail, throughout which like reference characters 95 designate like parts:

The numeral 1 designates the usual wall boards disposed and nailed across the exterior of the studding and other framework of a stucco structure.

Flat against the exterior or face side of 100

the wall boards 1 is stretched my improved sheathing paper 2, which is temporarily secured to said boards by driving suitable fastening nails 3 thereinto through binding strips 4 attached to and extending transversely across said sheathing paper in spaced order and forming part thereof.

The sheathing paper 2, which is preferably made up in lengths of twenty-five feet or over, with a width of three feet or thereabout, embodies, preferably, the conventional asphaltum impregnated paper commonly known by the trade name of "building paper", and at present generally applied to the wall boards of stucco structures as a weather-proofing, prior to the application thereagainst of the stucco composition. The stucco composition is not shown in the drawings.

The binding strips 4, which extend transversely across the face of the main body portion of the sheathing paper 1, preferably more or less at right angles with the side edges thereof, and which form an integral part thereof, are intended to be "factory built" thereonto, preferably by cementing them thereagainst by means of a suitable adhesive having preferably an asphaltum base. I have found in practice that molten, or liquid, asphalt, applied while hot, provides an entirely practical and satisfactory adhesive for binding the strips to the sheathing paper. Other means for securing them may be employed however, if desired.

The binding strips 4 are made up, preferably, of "building paper" stock, generally similar in composition to that embodied in the sheathing paper 1, but having, preferably, a greater mineral, or asphaltum, content, thereby making them relatively softer and more pliable and more yielding resiliently than the body portion of the sheathing paper. A nail or like fastening device 3 operatively driven into, or through, them will cause the material forming their composition, to yield resiliently, resistingly laterally relative to the shank of the nail, and to become compressed immediately adjacent the latter and bind and press thereagainst, thereby preventing any leakage of water between the nail shank and said material through which it is driven. The binding strips 4 also act as cushions against which the furring devices 5, cooperating with the fastening nails 3 in securing the metal lath, are seated, and into the face of which said furring devices usually become partly embedded (see Figs. 4 and 5) by forceably driving the nails into their supports in order to firmly bind the lath against the apexes of said furring devices. This drawing into or embedding of the furring devices in the face of the binding strips, causes the material of the latter, adjacent the nail, to become compressed and thereby bind more firmly against the shank of the nail, which

operates further to prevent water leakage along the sides of said shank.

In applying furred metal lath to the plain commercial building paper heretofore used in stucco work, the furring devices were necessarily disposed directly against the body of the relatively thin paper, which usually resulted in it being torn by said devices as they were forced thereagainst and thereinto by the driving of the fastening nail, subjecting the paper at such damaged places to leakage, and thereby defeating the primary purpose for which sheathing paper is employed, namely, to prevent water from the exterior leaking through the paper to the woodwork of the structure.

In Fig. 4 of the drawings, the furring element 5, of which a median sectional view is shown, comprises a metal cup-shaped device having an annular rolled flange 5a seated against and slightly embedded in the face of the binding strip 4, while between the upper end or apex of the device and the head of the nail 3, is pinched a strand of the metal lath 6. Fig. 5 shows a median sectional view of a furring device that is cylindrical in cross section, preferably formed of fibrous material. As will be observed, the fastening nails of both said figures pass substantially centrally through the furring device 5, through the binding strip 4, and sheathing paper 2, and are projected a distance into the wall boards 1.

In Fig. 7 the furring element is eliminated and the metal lath 6 secured directly against the binding strip 4. This method may be employed in work in which stucco composition of less thickness is to be applied than is commonly the case when furring devices are used.

While I have found in practice, that binding strips about one and one-half inches wide, and from $\frac{3}{2}$ to $\frac{1}{8}$ of an inch in thickness, and spaced about eight inches apart, center-to-center, provides thoroughly practical and efficient sheathing paper useful for the purposes herein set forth, binding strips having dimensions other than those above mentioned, and strips spaced distances apart other than stated, may be employed and spaced as desired and as found best suited to the work to be performed, without departing from the spirit of my invention.

The body portion of my improved sheathing paper is intended to be formed principally of vegetable fibre and the necessary binder therefor, impregnated with asphaltum, the latter intended for making it water resistant; the binding strips, while they embody, preferably, the same general composition, are intended to be provided with a larger percentage of asphalt, thereby providing them with a denser, but more pliable and more yielding body.

I claim:

1. In sheathing paper of the character de-

130

scribed, a sheet of paper, a plurality of relatively narrow spaced binding strips disposed flat against one side thereof and cemented thereto and forming an integral part thereof, said strips formed of a composition containing a larger percentage of mineral substance than is contained in the composition comprising said sheet of paper.

2. In sheathing paper of the character described, a sheet of paper impregnated with asphalt, a plurality of relatively narrow binding strips disposed in spaced order flat against one side thereof and attached fixedly thereto, said strips formed of a composition including asphalt, the percentage of asphalt being greater in said strips than in said sheet of paper.

3. In sheathing paper of the character described, a sheet of paper impregnated with a waterproofing substance, a plurality of relatively narrow binding strips secured in spaced relation to a face of said sheet of paper, said strips being impregnated with a waterproofing substance and being softer and more pliable than the paper sheet whereby same are adapted to be spread by the shanks of fastening devices driven therethrough and to be compressed entirely around the shanks of said fastening devices, to prevent any leakage of water through the holes in the strips formed by the shanks of the fastening devices.

4. A sheet of sheathing paper, and binding strips carried thereby adapted to receive fastening devices driven therethrough to secure the sheet to a support, said strips being composed of relatively soft and pliable and resiliently yielding material whereby same are adapted to be spread by the shanks of the fastening devices driven therethrough and to be compressed entirely around the shanks of the fastening devices to prevent any leakage of water through the holes in the strips formed by the shanks of the fastening devices.

In testimony of the foregoing being my own, I have hereunto affixed my signature this 24th day of May, 1929.

CARL GILMORE.
